UNITED STATES PATENT OFFICE.

OTTO N. MOORE, OF INDIANAPOLIS, INDIANA, ASSIGNOR OF ONE-HALF TO JOHN W. MOORE, OF INDIANAPOLIS, INDIANA.

REGULATOR FOR FLUID-FLOW.

1,267,577.

Specification of Letters Patent.

Patented May 28, 1918.

Application filed February 8, 1916. Serial No. 76,055.

To all whom it may concern:

Be it known that I, Otto N. Moore, a citizen of the United States, residing at Indianapolis, in the county of Marion and State of Indiana, have invented a new and useful Regulator for Fluid-Flow, of which the following is a specification.

My invention is particularly applicable and is primarily designed for use in connection with airlift pumps, to maintain substantially constant the inflow of air into the pump and minimize or wholly prevent "slugging"; but it is applicable in its broader aspects for other uses where it is desirable to maintain a constant flow of fluid.

In airlift pumps, the injection of air in the pump produces a mixture of air and water which is lighter than the water itself, so that the water rises through the eduction pipe and is discharged therefrom. In this action there is developed a certain instability, which produces a more or less rhythmic rise and fall of the water in the well casing and in consequence a more or less rhythmic variation in the resistance offered to the injection of the air; and this results in variations in the injection of the air into the water at the airlift pump, and these variations, at least in large part, produce the objectionable "slugging".

It is the object of my present invention to maintain the flow of fluid substantially constant, especially air for an airlift pump. I do this by providing a valve which controls the flow of fluid, and operate such valve by a vane which is moved upon changes in the velocity of the stream of fluid. Provision is made for obtaining any desired valve opening for a definite fluid velocity, and if desired for retarding the motion of the vane and valve, though my device does not require such retarding device, and in many cases is more desirable without it.

The accompanying drawing illustrates my invention. Figure 1 is a diagrammatic view of a well equipped with an airlift pump having its flow of air controlled by my invention; Fig. 2 is a sectional view of the air-flow controller, showing the interrelation of its parts; and Fig. 3 is a fragmentary internal development of the device, being taken as a section on the curved line 3—3 of Fig. 2.

Within the well casing 10 is located the 55 eduction pipe 11, having within it near its lower end a suitable air nozzle 12 at the proper submergence. This air nozzle 12 is shown as a simple open ended pipe, but it may take any of the forms which have been 60 developed for such nozzles, my invention being independent of the character of the air lift pump. The air nozzle 12 is supplied by a suitable air supply pipe 13, shown as projecting downward into the well casing 10 65 outside the eduction pipe 11, though such location is not necessary, and the pipe 13 is supplied with air from any suitable source through my fluid-flow regulator 14, which is conveniently located at the top of the well 70 so as to be as near the nozzle 12 as possible and thus minimize the storage capacity of the line between such regulator and such nozzle.

My fluid-flow regulator in its preferred 75 form has a cylindrical casing 20 having a removable cover 21 in which may be a window 22 to permit the operation of the device to be observed. The casing 20 has a fixed central pivot pin 23 on which is pivoted a 80 moving member 24 having two arms 25 and 26. At the outer end of the arm 25 is mounted an arc-shaped valve plate 27, which as the member 24 is moved covers and uncovers to a greater or less extent a slot 28 in 85 the cylindrical side wall of the casing 20, which slot opens through the air outlet fitting 29 into the pipe 13, which is connected thereto. The slot 28 is preferably parallel-sided, as is clear from Fig. 3, so that it 90 varies in size uniformly for definite movements of the valve plate 27. The arc-shaped valve plate 27 preferably has a slight clearance from the inner side wall of the casing 20, both to facilitate its movement and to 95 allow a slight leakage around it to the slot 28 at all times. The arm 26 of the movable member 24 carries a vane 30 which co-operates with the open end of an inflow nozzle 31 adjustably fastened by a screw 32 in the 100 discharge end of an air-inflow opening 33 which is connected by the pipe 34 to the source of air supply. The inrushing air from the inflow nozzle 31 strikes the vane 30 and tends to move it and the entire member 105 24 to a greater or less degree in a clockwise direction. An adjustable spring 35 connect- ed between the arm 25 and an adjusting

2
screw 36 extending through the wall of the casing 20 tends to move the member 24 in a 5 counterclockwise direction against the action of the inrushing air stream on the vane 30. Thus the position of the movable member 24 and therefore of the valve plate 27 is always that which produces an equilibrium between the spring 35 and action of the inrushing air stream on the vane 30.

10 Therefore, the flow of air through the slot 28 and into the air supply pipe 13 is controlled by the velocity of the air discharged against the vane 30. When by reason of the rhythmic variation in the water head at the 15 air pump nozzle 12 the resistance to the discharge of air from such air pump nozzle 12 rises, the velocity of the air discharge is decreased both at the air pump nozzle 12 and at the inflow nozzle 31, thereby diminishing 20 the force of the air stream on the vane 30 and permitting the spring 35 to predominate, thereby causing the member 24 to move in a counterclockwise direction to cause the valve plate 27 to uncover more of the slot 28, so as to increase the volume of air supplied 25 to the pipe 13 and thereby to the air pump nozzle 12 and counteract by such additional supply of air the increased resistance offered to the discharge of air from such air pump nozzle 12. When by reason 30 of such rhythmic variation in the water head at the air pump nozzle 12 the resistance to the discharge of air from such air pump nozzle 12 falls, the velocity of the air 35 discharge is increased both at the air pump nozzle 12 and at the inflow nozzle 31, thereby increasing the force of the air stream on the vane 30 so that it predominates over the spring 35, thereby causing the member 24 to 40 move in a clockwise direction to cause the valve plate 27 to cover more of the slot 28, so as to decrease the volume of air supplied to the pipe 13 and thereby to the air pump nozzle 12 and counteract by such additional 45 supply of air the diminished resistance offered to the discharge of air from such air pump nozzle 12. As a result of this, the member 24 vibrates synchronously with the rhythmic changes in the water head in the 50 well, and maintains a substantially constant flow of air from the air pump nozzle 12, thus diminishing and in many cases totally preventing the objectionable slugging, so as to produce a uniform discharge from the 55 eduction pipe 11, and also largely reducing the rhythmic variations in water head which tend to produce such slugging.

In some cases it is desirable, though in many cases it is not desirable, to diminish 60 the vibrations of the movable member 24. When this is desired, I provide a dash pot 40, connected between the wall of the casing 20 and such member 24. This dash pot 65 is shown in Fig. 2 as having its cylinder pivotally mounted by a pivot pin 41 on the

wall of the casing 20 and its piston rod pivotally mounted by a pivot pin 42 on the arm 26.

A manually adjustable arc-shaped plate 45 is slidably mounted against the inner 70 wall of the casing 20 on the opposite side of the slot 28 from that with which the valve plate 27 coöperates. The plate 45 works behind a guide pin 46, and is held in place by a transverse bar 47 carried by a pin projecting through the wall of the casing 20, and is provided with rack teeth 48 which coöperate with a pinion 49 carried by the inner end of a shaft 50 mounted in the wall of the casing 20 and provided at its outer end 80 with a knurled head 51 for operating it. By turning the knurled head 51, the plate 45 is slid circumferentially so as to cover more or less of the slot 28 at the opposite end of such slot from that with which the valve plate 27 coöperates. This permits the effect of a given movement of the movable member 24 to be varied.

The operation of the device may also be adjusted by the screw 36 and by shifting 90 the inner end of the spring 35 to different ones of the holes 55 in the arm 25. It may be adjusted still further by loosening the screw 32 and sliding the inflow nozzle 31 longitudinally of the tube 33 so as to vary 95 the position of the valve 27 for a given opening between the vane 30 and the end of the nozzle 31. A further adjustment may be provided by varying the size of the inflow nozzle 31, as by inserting within it a 100 supplemental tube 56 of the desired size; this varies the velocity of the air stream against the vane 30, and thereby varies the action of the device.

I claim as my invention:

105
1. A regulator for fluid flow, comprising a chamber having a fluid supply line thereto and a fluid discharge line therefrom, two valve members controlling the entrance to said fluid discharge line from said chamber, one of said valve members being manually operated, and a vane controlled by the velocity of fluid discharge from the fluid supply line into said chamber for operating the other valve member, said two valve members being movable over the entrance to said fluid discharge line from opposite sides thereof.

120
2. A regulator for fluid flow, comprising a chamber having a fluid supply line thereto and a fluid discharge line therefrom, two valve members controlling the entrance to said fluid discharge line from said chamber, one of said valve members being manually operated, and a vane controlled by the velocity of fluid discharge from the fluid supply line into said chamber for operating the other valve member.

125
3. A regulator for fluid flow, comprising a chamber having a fluid supply line thereto

and a fluid discharge line therefrom, two valve members controlling the entrance to said fluid discharge line from said chamber, one of said valve members being manually operated, and a vane controlled by the velocity of fluid discharge from the fluid supply line into said chamber for operating the other valve member, said two valve members being movable over the entrance to said fluid discharge line from opposite sides thereof, said vane-operated valve member being spring-pressed toward open position and being movable by said vane toward closed position.

15 4. A regulator for fluid flow, comprising a chamber having a fluid supply line thereto

and a fluid discharge line therefrom, two valve members controlling the entrance to said fluid discharge line from said chamber, one of said valve members being manually operated, and a vane controlled by the velocity of fluid discharge from the fluid supply line into said chamber for operating the other valve member, said vane-operated valve member being spring-pressed toward open position and being movable by said vane toward closed position.

In witness whereof I have hereunto set my hand at Indianapolis, Indiana, this first day of February, A. D. one thousand nine hundred and sixteen.

OTTO N. MOORE.
